UNITED STATES PATENT OFFICE.

WILLIAM HENRY KNICKREHM, OF SOMONAUK, ILLINOIS.

COMPOSITE RAILWAY-TIE.

1,176,570.

Specification of Letters Patent. Patented Mar. 21, 1916.

Application filed October 18, 1915. Serial No. 56,527.

To all whom it may concern:

Be it known that I, WILLIAM H. KNICKREHM, a citizen of the United States, residing at Somonauk, in the county of DeKalb and State of Illinois, have invented certain new and useful Improvements in Composite Railway-Ties; and I do declare the following to be a full, clear, and exact description of the invention, such as will enable others skilled in the art to which it appertains to make and use the same.

This invention relates to improvements in composite railway ties, the improvement residing particularly in the metallic reinforcing frame used therein.

The primary object of my invention is to provide an improved means for retaining wooden cushioning blocks within the tie structure upon which the track rails are designed to be placed.

With this general object in view, my invention consists in the novel features of construction, combination and arrangement of parts which will hereinafter be more particularly described and claimed and shown in the drawing wherein:

Figure 1 represents a side elevation of one of my improved ties, portions thereof being in section; Fig. 2 is a detail plan view of one end of this tie showing a portion of a rail thereon; Fig. 3 is a vertical section taken on the plane of the line 3—3 of Fig. 1; Fig. 4 is a perspective view of the reinforcing frame; and Fig. 5 is a similar view of the spacing bar.

My improved tie as covered by the present application comprises a concrete body portion 1 in which an improved metallic frame structure is adapted to be embedded. This concrete body may be molded or pressed about the frame in any desired manner, it being merely essential that the body portion present a general outline of the usual tie. This frame is formed of two laterally spaced angle bars 2 substantially the length of the cross tie, said bars being connected by two pairs of cross bars 3 and 4. The pairs of cross bars 3 and 4 are spaced apart a distance equal to that which the track rails are spaced apart, and are also formed of angle bars such as compose the bars 2. The opposite ends of the vertical flanges 5 of these angle bars 3 and 4 are cut away to leave an upright flange which is of a length corresponding to the distance which it is desired to space the bars 2 apart. The projecting

ends 6 of the horizontal flange 7 of the bars 3 and 4 are secured by bolts or rivets or other fastening means 8 to the upper side of the horizontal flanges of the bars 2 as best disclosed in Figs. 3 and 4. The bars 3 and 4 are each spaced apart a sufficient distance to readily receive cushioning elements 9, here shown in the form of substantially rectangular wooden blocks.

The blocks 9 are set in U-shaped members 10 which are positioned between the bars 2 and have their upright flanges 11 secured to the inner faces of the vertical flanges of the cross bars 3 and 4. This construction allows the concrete to be molded around the frame structure before placing the wooden blocks therein. In order to retain the blocks 9 within the U-shaped members 10, I provide substantially rectangular wear plates 12 which overlie said blocks 9 and the adjacent portions of the concrete portion of the tie. These wear plates 12 are spaced from the tie by means of additional cushioning members 13 also of wood, which act as deadening plates to prevent the unnecessary noise which would occur if the metallic wear plates were placed directly on the concrete tie. These cushioning elements 13 are of substantially the same size as the wear plates 12 and have openings 14 formed in their end portions which are adapted to align with openings formed through the plates 12 for the reception of bolts 15 which serve to retain the plates 12 and 13 in operative position on top of the tie. These bolts 15 are here shown as four in number, one being used at each end of each of the plates, and are positioned between the bars 2. It is evident when the concrete is molded about the frame, these bolts will be securely held in position in the tie with their threaded ends projecting through the openings in the plates 12 and 13, a nut 16 being threaded upon each to securely clamp said plates in position. Additional openings 17 are formed in the metallic wear plates 12 for the reception of the usual spikes 18 used for securing the track rails R to the ties.

The innermost bolts 15 are connected by a spacing bar 19 which preferably underlies the concrete body portion 1 as shown in Fig. 1. While I have shown the spacing bar 19 as being outside of the concrete body portion, it is obvious that it may be molded within said body portion and serve the same purpose. This bar not only acts as a spac-

ing member but also materially strengthens the frame.

From the foregoing description taken in connection with the accompanying drawing, it is evident that I have produced a very simple yet improved form of reinforcing frame for concrete railway ties and one which will last indefinitely if the concrete is properly molded thereabout and it is also evident that when the wooden cushioning elements 9 and 13 become rotten or decayed, they may be replaced simply by removing the wear plates 12 when additional elements may be inserted.

15 I claim as my invention:

1. A reinforcing frame for composite railway ties comprising a pair of laterally spaced angle bars, two pairs of spaced apart cross bars connecting said angle bars, said bars being spaced apart the distance the track rails are to be spaced, a U-shaped member having upright flanges secured between the spaced apart cross bars, a rail cushioning element disposed in each of said

25 U-shaped members, and means for holding said elements in operative position.

2. A reinforcing frame for composite railway ties comprising a pair of laterally spaced angle bars, two pairs of spaced apart cross bars connecting said angle bars, said bars being spaced apart the distance the track rails are to be spaced, a U-shaped member having upright flanges secured between the spaced apart cross bars, a rail cushioning element disposed in each of said

35 U-shaped members, a wear plate disposed over each of said cushioning elements upon which the rails are adapted to rest, and means for securing said plates in operative position.

40 3. A reinforcing frame for composite railway ties comprising a pair of laterally spaced angle bars, two pairs of spaced apart cross bars connecting said angle bars, said bars being spaced apart the distance the track rails are to be spaced, a U-shaped member having upright flanges secured between the spaced apart cross bars, a rail cushioning element disposed in each of said

45 U-shaped members, a wear plate disposed over each of said cushioning elements and adapted to overlie the adjacent portions of the

tie, an additional cushioning element interposed between each of said plates and the tie, and means for securing said plates and 55 the additional cushioning elements in operative position.

4. A reinforcing frame for composite railway ties, comprising a pair of laterally spaced angle bars, two pairs of spaced apart 60 cross bars connecting said angle bars, said bars being spaced apart the distance the track rails are to be spaced, a U-shaped member having upright flanges secured between the spaced apart cross bars, a rail 65 cushioning element disposed in each of said U-shaped members, a substantially rectangular wear plate disposed over each of said cushioning elements and adapted to overlie the adjacent portion of the tie, an additional 70 cushioning element interposed between each of said plates and the tie, and bolts adapted to extend between the pair of angle bars and through each end portion of the wear plates and the last mentioned cushioning 75 elements.

5. A reinforcing frame for composite railway ties, comprising a pair of laterally spaced angle bars, two pairs of spaced apart cross bars connecting said angle bars, said 80 bars being spaced apart the distance the track rails are to be spaced, a U-shaped member having upright flanges secured between the spaced apart cross bars, a rail cushioning element disposed in each of said 85 U-shaped members, a substantially rectangular wear plate disposed over each of said cushioning elements and adapted to overlie the adjacent portion of the tie, an additional cushioning element interposed between each 90 of said plates and the tie, bolts adapted to extend between the pair of angle bars and through each end portion of the wear plates and the last mentioned cushioning elements, and a spacing bar connecting the innermost 95 pair of bolts.

In testimony whereof I have hereunto set my hand in presence of two subscribing witnesses.

WILLIAM HENRY KNICKREHM.
